CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE.

SHIPPING DRUM.

Application filed October 13, 1927. Serial No. 225,908.

This invention relates broadly to sheet metal barrels or drums, and more specifically to a removable closure for such containers.

The primary object of the invention is to provide a sheet metal drum adapted for use as a container for chemicals in powder form, embodying a head provided with an improved form of removable closure which may be conveniently applied and removed and which, when in position, is practically proof against leakage of its powder contents.

A further object is to provide a removable cover for drums which may be conveniently removed without distortion thereof and which, consequently, is adapted for re-use.

In describing the invention in detail, reference is herein had to the accompanying drawings, in which—

Figure 1 is a head end elevation of a metallic drum embodying my invention;

Figure 2 is a partial section on line 2—2, Fig. 1;

Figure 3 is an enlarged detail view, in top plan, of a portion of the retaining ring; and—

Figure 4 is an enlarged detail section illustrating the joint between the drum head and the closure.

Referring to said drawings, 1 designates the body, and 2 the head, of a sheet metal barrel or drum, said head being seamed or otherwise suitably attached to said body. Provided in the head 2, preferably in a central location, is a circular opening through which ac-

cess is had to the interior of the drum for the introduction and removal of the powdered chemical or other material which constitutes the contents of the drum. Said opening is defined by a flange 3 which depends vertically

from a horizontal ledge 4 formed on the barrel head and disposed in a plane below the main body portion of said head. Said ledge is the lower of two relatively spaced parallel members, the upper member 5 having mate-

rially less width than said ledge and being located in underlying seated relation to the adjacent edge portion of the main body of the head, as shown in Figs. 2 and 4. Said member 5, ledge 4 and flange 3 are integral parts of the head 2, the latter having its inner edge portions bent to shape said parts. The outer portion of the lower member or ledge

4 is joined to the corresponding portion of the upper member 5 by an arcuate bend 6 formed in the metal, as shown.

55

The inner edge portion of the ledge 4 constitutes a seat adapted to receive thereon a horizontal flange 7 formed annularly upon the upper edge portion of the vertical wall 8 of a downwardly dished sheet-metal closure 9 which is designed to fit snugly within the neck formed by the depending opening-defining flange 3. Said seating flange 7 is made of such narrow width that introduction and removal of the closure 9 past the line of junction of the member 5 with the main body of the drum head 2 is readily permitted.

60

For securing the closure in its aforesaid seated position, an expandable retaining ring 10 of split, or open, form is provided, said ring consisting of a circular vertically disposed band 10^a having formed on the upper edge portion thereof an integral horizontal annular flange 10^b. Said ring in its contracted form is adapted for introduction to a position in which its band portion 10^a is received loosely within the embrace of the upright wall 8 of the closure 9 with its flange 10^b seated upon the flange 7 of the closure. Following such introduction, the ring is ex- 70

75

panded to seat its band portion closely against said neck and to project the edge of its flange portion beneath the member 5 of the head, as shown in Figs. 2 and 4, in which position said ring is effectually held against chance dis- 80

85

placement.

The ledge 4 is spaced from the overhanging member 5 a distance substantially equal to the combined thicknesses of the closure seating flange 7 and the ring flange 10^b. Thus, when the retaining ring is expanded into place, its flange 10^b assumes closely underlying relation to the head member 5, as shown.

90

The retaining ring 10 has mounted, as by spot-welding, upon the meeting ends of its band portion 10^a the opposite ends of a non-resilient or malleable metal strap 11 which initially possesses an inwardly bowed form, said bowed strap serving to hold said ring in its contracted form until the latter has been introduced in seated relation to the closure. Following such introduction, the ring is ex- 95

100

panded to its closure retaining position by flattening the bow of said strap against the

band portion of the closure, effected by means of a hammer or other suitable form of tool. To withdraw the retaining ring for releasing the closure, the edge of a screw driver or other suitable instrument may be introduced between the strap 11 and the adjacent wall of the ring and employed to pry said strap into bowed form for effecting the required contraction of the ring.

10. What is claimed is—

1. A sealing device for use with receptacles having seats of substantially C-form in cross-section and having covers provided with flanges engaged in said seats, comprising a split ring having a vertical portion and a horizontal portion which latter engages on top of the flange and against the top wall of the seat, and an integral metal strap formed independent of the ring and having each of its ends rigidly affixed to the respective ends of the ring and having a central portion bowed toward the center of the ring and bridging the space between the ring ends, said strap being formed of malleable material so as to cause same to be flattened against the ring
- 15
- 20
- 25

to expand the latter by the delivery of blows against the bowed portion of the strap.

2. A sealing device for use with receptacles having seats of substantially C-form in cross-section and having covers with a peripheral portion of the latter engaged in said seats, comprising a split ring having a part engaged between the cover and a wall of the seat, and an integral malleable element formed independent of the ring and rigidly secured at its ends to the respective ends of the split ring and having a displaceable part formed to receive hammer blows so as to be flattened for the purpose of expanding the ring.

3. A sealing device for receptacle covers, comprising a split ring engageable with the receptacle and cover, and an integral malleable element formed separately from said ring and rigidly secured at its ends to the respective ends of the split ring and having a displaceable part formed to receive hammer blows so as to be flattened for the purpose of expanding the ring.

In testimony whereof, I affix my signature.

CHARLES H. ROLLASON.
